UNITED STATES PATENT OFFICE

172,950

LAMP OR SIMILAR ARTICLE

Edwin I. Cole, Eagle, Wis., assignor to The Stiffel Company, Chicago, Ill., a corporation of Illinois

Application February 4, 1954, Serial No. 28,834

Term of patent 7 years

(Cl. D48—20)

To all whom it may concern:

Be it known that I, Edwin I. Cole, a citizen of the United States of America, residing at Eagle, county of Walworth, State of Wisconsin, have invented a new, original, and ornamental Design for a Lamp or Similar Article, of which the following in a specification, reference being had to the accompanying drawing forming a part hereof.

Figure 1 is a perspective view of a lamp or similar article, showing my new design.

The dominant features of my design reside in those portions shown in full lines.

I claim:

The ornamental design for a lamp or similar article, as shown and described.
